HIS ATTORNEYS.

UNITED STATES PATENT OFFICE.

FRANK X. LAUTERBUR, OF SIDNEY, OHIO.

ASH SIEVE.

Application filed July 20, 1923. Serial No. 652,698.

To all whom it may concern:

Be it known that I, FRANK X. LAUTERBUR, a citizen of the United States, and a resident of Sidney, in the county of Shelby and State of Ohio, have invented certain new and useful Improvements in Ash Sieves, of which the following is a full, clear, and exact description, reference being had to the accompanying drawings, forming part of this specification.

My invention relates to receptacles for sifting ashes, particularly designed for home use, and the object of my invention is to provide an apparatus in which ashes from grates, stoves, furnaces and the like may be deposited with the ordinary shovel, and effectively sifted without the escape of dust when the deposit is made and the ashes sifted by the rotation or agitation of the sifting screen.

In the handling of ashes, it is comparatively easy to fill the shovel from the ash box of the stove or furnace without dust, but practically impossible to prevent the flying of dust to cover the operator when the contents of the shovel are deposited in the ash can, no matter how carefully the deposit is made, and my invention is especially directed to prevent the escape of dust when the deposit is made.

The invention consists of that certain novel construction and arrangement of parts to be hereinafter particularly pointed out and claimed, whereby the above result is attained.

In the drawings:

Figure 1 is a front elevation of my improved apparatus.

Figure 2 is a central vertical section of the same.

Figure 3 is a top plan view.

Figure 4 is a sectional detail through the middle door of the device.

Figures 5 and 6 are cross sections taken on the lines 5—5 and 6—6 of Figure 7 looking in the direction of the arrows of the rotary sifting sieve construction.

Figure 7 is a longitudinal section of same.

Figure 8 is a detail section of the rotary sieve construction illustrating the position of the ash shovel when inserted on the sieve before dumping.

Figure 9 is a similar view with the shovel turned vertically for dumping.

Figure 10 is a front view and Figure 11 a side view of the catch for the sifting handle.

The outer casing 1 for the apparatus is made of any suitable material, preferably sheet metal and is formed tight and dust proof throughout, so as to prevent any escape of dust through container joints.

Mounted in the upper portion of this container is a rotary ash receiver 2. The front and rear carrying walls 3, 4, of the rotary sieve are of relatively light material such as steel or iron sheet with the back wall entirely closed and with openings 5 and 6 in the front wall to register, when the sieve is in normal position, with doors 7 and 8 hinged, as will be described, to the outer casing.

The sieve is made up of wire mesh 9 of the proper size or of perforated plate secured in the shape of a cylinder to the front and back walls and one portion of this cylinder is formed with a projecting flat portion forming a horizontal trough 10, when the sieve is at rest, and the bottom of this trough portion may be solid or perforated as desired. In order to insure a normal position of the sieve with this trough at the bottom I secure a weighted plate 12 along this bottom section. The sieve construction is mounted on a shaft 13 which is bent downwardly at the middle portion with vertical portions 14, which permit the end walls 3 and 4 to be effectively and easily secured to the shaft by clips 15, 15, and held rigid thereon, while the ends of the shaft find suitable bearing in blocks 16, 16, on the outer casing. The front end of this shaft is provided with a suitable crank handle 17 for rotation of the sieve.

In the lower portion of the casing is located a portable ash receiver 19 with fixed side handles 18 and also a front handle 20 for convenience in withdrawing it from the casing when filled, and in order to direct the ashes which pass through the screen into this ash can 19, I provide a chute 22 above the can to direct the ashes from the sieve into the can.

To return now to the construction of the upper part of the apparatus, the door 7 covering the opening 5 through which the ashes are deposited into the sieve, is hinged on a rod 23 journaled in clips 24 on the out-

side of the casing, with the door normally held shut by the coiled spring 25 mounted on the rod. The outer end of the hinge rod has a crank 26, coupled by connecting rod 27, with a foot treadle 28, which is pivotally mounted on the end of the casing. When the operator depresses the foot treadle, the hinge rod 23 is rocked to open the door 7. This door 7 is provided with a slot 29 in its lower edge which slot is covered by a flap 30 hinged to the door. Below the door 7, and opposite the opening 6 is the door 8 which is secured to the pintle 31 pivoted in clips 32 on the casing and one end of this pintle has a crank to which is secured a coiled spring 33 with the other end secured to the case so that the door 8 is held shut by spring tension, a handle 34 being provided to open the door.

20 The lower compartment containing the ash can 19 is also provided with a casing door 35 hinged at 36 and opened by handle 37.

25 The crank 17 for rotating the sieve is normally held in horizontal position, as shown in Figure 1, by a pivoted latch 38 (Figures 10 and 11), which can be turned outwardly to engage and lock the crank or turned down so as to release the crank and permit its 30 operation. As heretofore stated the weight 12 also tends to hold the crank in horizontal position with the openings 5 and 6 in register with the doors 7 and 8.

35 The mode of operation will be obvious from the foregoing description. The operator fills his shovel, illustrated at 40, with ashes and with his foot depresses the treadle 28, which opens the door 7 and allows the shovel to be inserted through the opening 40 5 into the sieve receptacle. The operator then releases the foot treadle and the door 7 closes allowing the shank of the shovel to enter the slot 29. Then the operator dumps the ashes by turning the shovel as shown in 45 Figure 9. In this turning the shovel, there is no interference with the shaft 13 by reason of its downward bend, and this bend also enables me to locate the door opening lower and in a more convenient position for 50 the user. The ashes being dumped, the shovel is withdrawn, the door swinging outwardly to pass the shovel and then automatically closing. The operator then rocks or rotates the sieve shaking out all the fine 55 ashes, which pass the perforations or mesh and are received in the ash can 19.

60 The operator then opens the door 8 and shovels out any large or half burnt coal for reburning. When the ash can 19 is filled by opening the door 35, the can may be readily removed by the handle 20.

Having thus described my invention, what I claim as new, and desire to secure by Letters Patent, is:—

65 1. In a device of the character specified, a

closed outside casing with a sifting receptacle mounted therein adapted to be agitated and a container below the sifter to receive the sifted material, the sifting receptacle provided with openings in its end wall, one 70 above the other, and the casing having doors to cover the openings, the upper door hinged at the top to open outwardly, with means for causing the receptacle openings to register with the door openings, when the machine 75 is at rest.

2. In a device of the character specified, a closed outside casing with a rotatable sifting receptacle mounted therein adapted to be agitated and a container below the sifter to receive the sifted material, the sifting receptacle provided with openings, one 80 above the other, and the casing having doors to cover the openings, with means for causing the receptacle openings to register with the door openings, when the machine is at rest.

3. In a device of the character specified, a closed outer casing, a shaft journaled in the sides of the casing with a cylindrical sifting receptacle mounted on the shaft, openings in the end wall of the sifter, one above the other on either side of the shaft, with doors in the casing to register with said 90 openings when the machine is at rest, the upper door hinged at the top to open outwardly and slotted at its free edge to receive the handle of a shovel, when the door is closed with a flap hinged to the door to 95 close the slotted opening.

4. In a device of the character specified, a closed outer casing, a shaft journaled in the sides of the casing with a cylindrical sifting receptacle mounted on the shaft, openings in the end wall of the sifter, one above the other on either side of the shaft, with doors in the casing to register with said 100 openings when the machine is at rest, the upper door hinged at the top to open outwardly and slotted at its free edge to receive the handle of a shovel, when the door is closed with a flap hinged to the door to 105 close the slotted opening, with a flattened portion for the cylindrical receptacle in line with the lower opening for the reception of non-siftable material.

5. In a device of the character specified, a closed outside casing with a sifting receptacle mounted therein adapted to be agitated and a container below the sifter to receive the sifted material, the sifting receptacle provided with openings, one above the other, and the casing having doors to cover the 110 openings, the upper door hinged at the top to open outwardly and a foot treadle with connection therefor to the upper door, for opening same for deposit of ashes in the sifting receptacle.

6. In a device of the character specified, a closed outer casing, a shaft journaled in the 115

sides of the casing with a cylindrical sifting receptacle mounted on the shaft, openings in the end wall of the sifter, one above the other on either side of the shaft, with doors in the casing to register with said openings when the machine is at rest, the upper door hinged at the top to open outwardly and slotted at its free edge to re-

ceive the handle of a shovel, when the door closed with a flap hinged to the door to close 10 the slotted opening, the shaft of the sifting receptacle being formed with a loop to permit the turning of the shovel to dump the ashes.

FRANK X. LAUTERBUR.
